UNITED STATES PATENT OFFICE.

CYRA B. WATTLES, OF PROVIDENCE, RHODE ISLAND, ASSIGNOR TO THE SURFACING MACHINE COMPANY, OF PROVIDENCE, RHODE ISLAND, A CORPORATION OF RHODE ISLAND.

GRINDING OR POLISHING ROLL.

SPECIFICATION forming part of Letters Patent No. 779,386, dated January 3, 1905.

Application filed February 15, 1904. Serial No. 198,488.

To all whom it may concern:

Be it known that I, CYRA B. WATTLES, a resident of the city of Providence, in the county of Providence and State of Rhode Island, have 5 invented certain new and useful Improvements in Grinding or Polishing Rolls; and I do hereby declare that the following is a full, clear, and exact description thereof, reference being had to the accompanying drawings, and 10 to the figures of reference marked thereon, which form a part of this specification.

This invention has reference to improvements in a rotary disk or cylinder which has secured to its surface a skin or outer covering 15 of felt, sandpaper, emery paper or cloth, corundum, or other similar abrasive material for use in grinding or polishing.

The primary object of this invention is to so construct the internal mechanism of this 20 roll or disk that the outer grinding or polishing surface or skin—such as felt, sandpaper, or the like—may be readily attached to and detached from said roll, the internal mechanism being also arranged to automatically take 25 up the slack of said outer covering as it becomes stretched while on the rapidly-revolving cylinder by coming in contact with the work, thereby keeping a constant tension on the same until released for the purpose of re- 30 plishing.

The particular construction herein shown and described is especially designed and adapted for use on a machine for dressing or polishing wooden floors; but the same device 35 may be employed in grinding, buffing, or polishing rolls for jewelers' use or for any other purpose for which a roll of this character may be adapted.

In using the roll on the floor-dressing machine it is constructed of a double length—that is, two separate pieces or widths of sandpaper or other polishing or abrasive material are used, each covering the roll for one-half of its length, and a separate tension mechanism for tightening each piece is used. In practice this construction is found to give the best results, especially when the long rolls

are used, for reasons hereinafter more fully described.

The invention consists of other novel features and parts and combinations of the same, as will be fully described hereinafter and then pointed out in the appended claims.

A practical embodiment of the invention is represented in the accompanying drawings, 55 forming a part of this specification, in which similar characters of reference indicate corresponding parts in all the views.

Figure 1 is a central sectional elevation showing the interior of the roll and the two 60 separate tightening devices with the driving-pulley on the end of the shaft. Fig. 2 is an end view on line 2 2 of Fig. 1, showing a portion of the handle and lock-pawl by which the tension on the outer covering or skin is re- 65 leased and the holding-jaws opened to release the end of said covering. Fig. 3 is a sectional end view showing the jaws opened and the outer skin or covering released. This is done by inserting the handle and bringing the internal mechanism up to the central point, which position corresponds with that shown in Fig. 2. Fig. 4 is a sectional view on line 70 4 4 of Fig. 1, showing the skin or outer covering in place and being held under tension, 75 one end being secured in the bite of the jaws, the opposite end being bent back on the inside of the cylinder and held in place by the friction of the first end upon it. Fig. 5 is a detail view in perspective of the biting-jaw, 80 showing the teeth on the upper edge of the same. Fig. 6 is a detail view in perspective, showing the spring-actuated block, the upper portion of which forms a jaw against which the toothed jaw bites. Fig. 7 is a side eleva- 85 tion showing a flanged sleeve, the flange of which forms one of the heads in the cylinder. Fig. 8 shows the handle and latch or pawl by which the tension mechanism is brought to its central position and held and the jaws opened 90 to release the abrasive skin or covering. The locking-pawl shown drops into the notch, as shown in Fig. 2, to hold said spring-actuated mechanism in the desired position while the

outer covering is being replenished. Fig. 9 represents a portion of the cylinder in elevation, showing the slots in the same.

Referring to the drawings, at 1 is the shell, which is made in a tubular form and of any suitable material. When it is desired to use a long roll, I preferably cut two slots 2 and 3 through the periphery of this shell, which slots may be set staggering, or they may be made, as shown in the drawings, one on the opposite side of the cylinder to the other. This arrangement is made so as to avoid cutting one long slot the entire length of the cylinder, thereby weakening the shell too much for practical use. Then, again, by dividing up this opening the roll runs much smoother and without jar or vibration, as the other half of the roll, where the slot does not extend, has a continuous surface which keeps the roll from jumping, and much more satisfactory results are thereby attained. As I find it advisable to use two slots, I therefore for similar reasons find it advisable to use two pieces of sandpaper or the like and a duplicate set of mechanism at each end of the roll as a separate tension or take-up for holding and tightening each sheet of polishing or grinding material.

At 4 is the flange on the end of the sleeve or trunnion 5, the periphery of which flange is turned the size of the inside diameter of the shell and when in place forms a head for the same. The length of the sleeve 5 is one-half the length of the cylinder 1 and meets a corresponding sleeve in the center of said cylinder at 6 as it projects in from the opposite end of the same.

At 7 (see Fig. 6) is a double-winged block cut out at its center portion and having bearings at each end 8 and 9, by which bearings it is loosely mounted on the trunnion 5. The upper portion 10 of this block serves as one of the jaws by which the end 11 of the sandpaper or the like is held. At 12 is the toothed jaw-piece, also loosely mounted on the trunnion 5 by the bearings 14 14. On the upper edge of this jaw are set the teeth 13, (see Fig. 5,) which when closed puncture the end 11 of the sandpaper or the like, said teeth extending through the same and into corresponding holes 15 in the opposite jaw 10, made to receive them. These jaws are held together by the tension of the spring 16, which is mounted on the pin 17. This pin extends through the lower portions 18 of the block and also the downwardly-projecting portion 19 of the toothed jaw. At 20 is a washer which holds said spring in place, said washer being held onto the end of said pin by the cotter-pin 21. At 22 is a fixed stop piece or lug against which the downwardly-projecting end 19 of the toothed jaw rests when the mechanism is swung up to its central position, as shown in Fig. 3, for the purpose of opening said jaws. At 23 is the flat coil-spring, which has a number of turns around the sleeve 5, one end be-

ing secured at 24 to said sleeve, while the opposite end 26 engages and presses against the upper portion 10 of the rotatable block. At 27 is an end piece which is mounted on and fixed to the hub 8 of the block. This piece 27 might be made integral with this block, but for structural reasons is made separate and secured to the end of the hub. Into this piece is made the hole or recess 28 for the reception of the end 29 of releasing-handle 30. Around this shell is wrapped a layer of felt 31 or other cushioning substance, and around the cushioning substance is wrapped a layer of the polishing or abrasive faced material 32. This layer, as above described, is made in two parts, each part or piece covering one-half of the length of the roll.

The whole mechanism is mounted on a center shaft 36, to which the sleeves 5 are fixed. This shaft may be supported in any suitable manner. I have, however, shown the same supported at each end of the cylinder on bearing 37 37 and the whole as being driven through pulley 38 on the end.

In assembling the parts I find it of considerable advantage to be able to remove the head and sleeve, on which latter I mount the tension mechanism complete and replace the whole in the shell intact and secure the head in position.

The construction and mechanism at one end of the roll is an exact duplication of the opposite end.

For many purposes the rolls are used one-half of the length of that shown, and only one set of tension mechanism is required.

To secure the skin or covering to the roll, the first operation is to insert the end 29 of the handle through the slot 35 into the hole 28 and draw the tension mechanism above described up to the central position. (Shown in Figs. 2 and 3.) The end of the latch or pawl 35 will by its own gravity then drop into the said slot 34 and by bringing up against the end of the slot hold the said mechanism in position with the jaws open, as shown in Fig. 3. In carrying this mechanism up to its central position the lower end 19 of the toothed jaw 12 brings up against the stop-piece 22, while the opposite jaw 10 continues on, causing the two to draw apart or open. One end, 33, of the outer abrasive or polishing covering is then passed through the slot and bent back underneath on the inside of the shell, (see Figs. 2 and 3,) the opposite end, 11, being carried around the roll and passed down through the same slot between the open jaws 10 and 12, which stand ready to receive it. The handle 30 is then withdrawn from the hole 28, and, acting under the tension of the spring 23, the block commences to rotate, causing the jaw 10 to close on the toothed jaw 12, the teeth of which latter jaw, being under tension of spring 16, puncture the end 11 of the covering, firmly biting the same and holding it securely in its

grasp. When these jaws move forward with this end tightly held, the rough surface of the skin as it is drawn through the slot comes in contact with the corresponding surface of the 5 opposite end, securely binding the same and keeping it from withdrawing from the slot. The roll revolves very rapidly in the direction of the arrow, and as it comes in contact with its work the skin or outer covering naturally 10 gives and stretches, sometimes to a considerable degree, and were there no mechanism provided to take up this slack the covering soon becomes loose and goes to pieces; but by my method of continuously taking up the slack 15 and keeping the surface smooth and hard the life and efficiency of the outer covering are materially increased.

Having thus described my invention, what I claim and new, and desire to secure by Letters Patent, is—

1. In a grinding or polishing roll, a cylinder around which is wrapped or wound a covering of material, a rotatable spring-actuated jaw within said cylinder, a second jaw arranged to bite the end of said covering and move with the first jaw to take up the slack or stretch of the same automatically, and means for opening the jaws automatically when the tension is removed from the covering.

2. In a grinding or polishing roll, a cylinder around which is wrapped or wound a covering of material, a rotatable spring-actuated jaw within said cylinder, a second jaw arranged to bite the end of said covering by spring-pressure and move with the first jaw to take up the slack or stretch of the same automatically and means for closing the jaw automatically when the tension is applied.

3. In a grinding or polishing roll, a cylinder around which is wrapped or wound a covering of material, a rotatable spring-actuated jaw within said cylinder, a second spring-actuated jaw arranged to bite the end of said covering by spring-pressure and move with the first jaw to take up the slack or stretch of the same automatically, and means for opening the jaws automatically when the tension is released from the covering.

4. In a grinding or polishing roll, a cylinder around which is wrapped or wound a covering of material, a rotatable spring-actuated jaw pivotally hung within said cylinder, a second jaw also pivotally hung, means for causing these jaws to bite the end of said covering and take up the slack or stretch of the same automatically.

5. In a grinding or polishing roll, a cylinder around which is wrapped or wound a covering of material, a rotatable spring-actuated jaw pivotally hung within said cylinder, a second jaw also pivotally hung within said cylinder, spring-actuated means for causing these jaws to bite the end of said covering and take up the slack or stretch of the same automatically.

6. In a grinding or polishing roll, a cylinder around which is wrapped or wound a covering of material, a rotatable spring-actuated jaw pivotally hung within said cylinder, a second jaw also pivotally hung within said cylinder, spring-actuated means for causing these jaws to bite the end of said covering and take up the slack or stretch of the same automatically, and means for opening the jaws automatically when the tension is removed from the covering.

7. In a device of the character described, a cylinder around which is wrapped or wound a covering of material for grinding or polishing, a spring-actuated jaw, a second spring-actuated jaw, arranged to rotate and carry the first jaw, both of which jaws are arranged to retain and draw one end of the covering tightly around the cylinder and means for holding the other end of said covering.

8. In a grinding or polishing roll, a cylinder around which is wrapped or wound a covering of material, a rotatable spring-actuated jaw within said cylinder, a second jaw arranged to bite the end of said covering by spring-pressure and move with the first jaw to take up the slack or stretch of the same automatically and means by which both ends of said covering are released when the tension is removed from said covering.

9. In a grinding or polishing roll, a cylinder around which is wrapped or wound a covering of material, a rotatable spring-actuated jaw pivotally hung within said cylinder, a second jaw also pivotally hung within said cylinder, spring-actuated means for causing these jaws to bite one end of said covering and take up the slack or stretch of the same automatically, and means for holding the other end of said covering.

10. In a grinding or polishing roll, a cylinder around which is wrapped or wound a covering of material, a rotatable spring-actuated jaw pivotally hung within said cylinder, a second jaw also pivotally hung within said cylinder, spring-actuated means for causing these jaws to bite one end of said covering and take up the slack or stretch of the same automatically, the other end of said covering being bent back on the inside of the cylinder and held in place by pressure from the rotating tension-jaws.

11. In a grinding or polishing roll, a cylinder around which is wrapped a covering of material, a rotatable spring-actuated jaw pivotally hung within said cylinder, a spring acting to rotate said jaw, said spring being mounted at the pivoting-point of the jaw, a second jaw also pivotally hung within said cylinder, spring-actuated means for causing these jaws to bite one end of said covering, and means for holding the other end of said covering.

12. In a grinding or polishing roll, a cylinder around which is wrapped a covering of material, a rotatable spring-actuated jaw piv-

totally hung within said cylinder, a spring acting to rotate said jaw, said spring being mounted at the pivoting-point of the jaw, a second jaw also pivotally hung within said cylinder, 5 and having a portion extending beyond the pivoting-point on the opposite side from the jaw, a spring acting on this extension to close said jaws, and bite one end of said covering in order that it may be stretched around the cylinder, and means for holding the other end of said covering.

13. In a device of the character described, a cylinder around which is wrapped a plurality of strips or sheets of material laid side by 15 side to cover its working face, individual slots through said cylinder in which the ends of each sheet are secured, each slot being made through the periphery at different points in the circumference and out of line with each 20 other to break the joint, and means by which the slack or stretch of said material may be taken up automatically.

14. In a device of the character described, a cylinder around which is wrapped a plurality of strips or sheets of material each sheet 25 covering but a portion of its working face, a slot in the periphery of said cylinder for each sheet of material used, each of said slots extending but a portion of the length of the 30 cylinder, and means for securing the ends of the material in said slots.

15. In a device of the character described, a cylinder around which is wrapped a plurality of strips or sheets of material, each sheet 35 covering but a portion of its working face, a slot in the periphery of said cylinder for each sheet of material used, each of said slots extending but a portion of the length of the 40 cylinder, and means by which the slack or stretch of the material may be taken up automatically.

16. In a device of the character described, a cylinder around which is wrapped a plurality of strips or sheets of material laid side by 45 side to cover its working face, individual slots through said cylinder in which the ends of each sheet are secured, each slot being made through the periphery at different points in the circumference and out of line with each 50 other to break the joint, two rotatable spring-actuated jaws each one being pivotally hung within said cylinder, and means for causing

these jaws to bite the end of said covering and take up the slack or stretch of the same automatically.

17. In a device of the character described, a cylinder around which is wrapped a plurality of strips or sheets of material laid side by side to cover its working face, individual slots through said cylinder in which the ends of 60 each sheet are secured, each slot being made through the periphery at different points in the circumference and out of line with each other to break the joint, two rotatable spring-actuated jaws each one being pivotally hung 65 within said cylinder, means for causing these jaws to bite the end of said covering and take up the slack or stretch of the same automatically, and means for opening these jaws automatically when the tension is released on the 70 covering.

18. In a grinding or polishing roll, a cylinder around which is wrapped a covering of material, a head in each end of said cylinder, an inwardly-projecting trunnion on each head, 75 two rotatable spring-actuated jaws pivotally mounted on each of said trunnions for engaging and tightening the material around said cylinder, two slots through the periphery of said cylinder, each slot extending but one-half the length of the working face of said cylinder and out of line with each other for the purpose of breaking the joint, each slot communicating with its individual set of jaws.

19. In a device of the character described, 85 a cylinder around which is wrapped a plurality of strips or sheets of material laid side by side to cover its working face, individual slots through said cylinder in which the ends of each sheet are passed, each slot being made 90 through the periphery at different points in the circumference and out of line with each other to break the joint, a head in each end of said cylinder, an inwardly-projecting trunnion on each head, two rotatable spring-actuated jaws pivotally mounted on each of said 95 trunnions for engaging and tightening the material which is wrapped around said cylinder.

In testimony whereof I have hereunto set my hand this 13th day of February, A. D. 1904. 100

CYRA B. WATTLES.

In presence of—

HOWARD E. BARLOW,
E. I. OGDEN.
